United States Patent Office.

EDWARD HEALY, OF CHICAGO, ILLINOIS.

Letters Patent No. 68,074, dated August 27, 1867.

IMPROVEMENT IN MECHANICAL MOVEMENT FOR WORKING SAWS, &c.

The Schedule referred to in these Letters Patent and making part of the same.

TO ALL WHOM IT MAY CONCERN:

Be it known that I, EDWARD HEALY, of Chicago, in the county of Cook, and State Illinois, have invented a new and useful Improvement in Sawing Machines; and I do hereby declare the following to be a full and exact description of the same, reference being had to the accompanying drawing, which is made a part of this specification, and which represents a perspective view of a sawing machine embodying my invention.

The machine, the subject of this invention, is more especially intended to perform such work as requires great velocity in the motion of the saw, and in which the intervals of the saw's action enable it to regain the requisite speed for effective operation.

The invention consists in the employment of a system of jointed levers for transmitting motion to the saw-shaft, said levers being extended by the motion of a rock-shaft and contracted by springs, as hereinafter described, their action being such as to secure a very rapid and steady motion, especially effective for the kind of work which is to be performed by the saw.

In order that others skilled in the art to which my invention appertains may be enabled to fully understand and use the same, I will proceed to describe it in detail.

In the accompanying drawing, A may represent a frame, constructed in any suitable manner, and supporting at one end the shaft which carries the circular saw B. Motion is communicated to the saw-shaft from the crank-shaft C' through the multiplying-wheels D D' D'' D''' and belts E E'. The crank C is driven by the pitman F, which is attached to the cross-head G mounted on suitable guides, and which is also jointed to two of a system of levers, H H H, which are jointed together in the manner represented, said levers serving to reciprocate the pitman by alternate extension and contraction. The levers H, at the end opposite their point of connection with the pitman F, are jointed to lugs on the main frame A. I is a rock-shaft, which is straddled by the adjacent levers H, as represented, and which is of sufficiently diminished size to permit said levers freely to expand and contract. The effective oscillation of the rock-shaft I is made to extend or elongate the levers H by winding upon its periphery the chains or other flexible connections J J, the ends of which are jointed respectively to lugs on the shaft I, and to two of the pins which connect together the ends of the levers H. Thus, when the shaft I is turned in one direction by hand, steam, or other power, the connected extremities of one set of the levers H are drawn together with considerable power, and the whole system of levers is thereby extended or elongated toward the crank C. The levers H, after being thus extended, are drawn back or contracted by the action of springs K, the upper and lower ones of which engage with pins l held by links L L, which are jointed to the levers H. The levers H occupy very little available space in the machinery, and they constitute a simple means for imparting a very high degree of velocity to the saw. Instead of applying the power directly to the levers, as above described, it may be transmitted thereto through an additional system of levers for the purpose of augmenting the speed to a still greater extent. A carriage, at P, may be employed for feeding the log to the saw.

Having thus described my invention, what I claim as new herein, and desire to secure by Letters Patent, is—

1. The combination of a system of levers H with a flexible connection, J, substantially as and for the purposes set forth.
2. The arrangement of the levers H, rock-shaft I, flexible connections J, and springs K, substantially as and for the purpose set forth.

To the above specification of my improvement in sawing machines I have signed my hand this third day of April, 1867.

EDWARD HEALY.
